FEEDING OF CARDS OR LIKE ARTICLES
FROM A STACKJohn Crighton, London, England, assignor to
American Machine & Foundry Company, New
York, N. Y., a corporation of New JerseyApplication February 6, 1937, Serial No. 124,497
In Great Britain February 13, 1936

14 Claims. (Cl. 271—44)

This invention relates to the feeding of cartons in packing machines and has particular reference to machines in which the lowest card-like article, such as a carton in a stack of cartons, is fed by a reciprocating tooth element or elements to feed rolls which deliver it to appropriate mechanism for subsequent operations.

The invention is particularly applicable to the feeding of the slide in connection with the packing of cigarettes in slide and shell cartons and for convenience will be described in association with such machine.

An object of the invention is to provide improved and simplified means for displacing or moving the carton into the path of the reciprocating feed tooth element or elements, such means being of the nature of a self-contained unit which may readily be applied to a feeding machine of the character in question.

According to a feature of the invention the card or slide displacing means comprises a pivotally mounted suction cylinder having a suction nozzle rigidly mounted thereon and means for oscillating the cylinder and for reciprocating the piston to produce the suction effect.

According to a further feature a stop may be provided adapted to hold the displaced card or portion thereof in the path of the reciprocating feed tooth or teeth when the suction nozzle is removed from the carton.

According to another feature the stack of slides may be provided with a three-point support, the leading point being arranged centrally and having a supporting surface inclined upwardly in the direction of feed.

Further features of invention will be herein-after described and defined in the claims.

In the accompanying drawings:—

Figure 1 is a side elevation partly in section showing the suction cylinder in its raised position,

Figure 2 is a plan, and

Figure 3 is an end elevation.

Figures 4 and 5 are end elevation and plan respectively of a modification concerning the tooth feed device.

In carrying the invention into effect according to one convenient mode in its application, by way of example, to the feeding of slides in connection with packing in slide and shell cartons, the slides 10 are arranged in a vertical stack and are adapted to be fed from the bottom of the stack.

The slides are arranged horizontally in a substantially flat condition and are positioned, at the corners of the sections which form the side

walls of the slide, by vertical adjustable guiding elements 11, 12, 13, 14. The two rear guides 13 and 14 are provided with supporting ledges 15. The forward tuck-in flaps 10a of the slide are supported by a centrally arranged tongue piece 16 the surface of which is inclined upwardly in the direction of feed so that the slide as it is fed forwardly is given a slight rising movement. The supporting surface 16a of the tongue 16 is curved transversely so that the slide engages the surface by point or line contact. Above the inclined curved surface 16a a stop 17 is provided which is mounted upon an adjustable carrier 18 so that the stop may be adjusted vertically to provide just sufficient space between it and the tongue piece 16 for a single slide to pass through. The lower face 17a of the stop 17 is curved as seen in Figure 3.

Adjacent the rear tuck-in flaps of the slides so as to project below the lowest slide in the stack is a movable stop element 19 which may comprise a flat spring. This stop 19 is carried by a bracket 20 and is adapted to give way as the rear flap 10b of a slide is brought down and then springs forward to engage above the slide flap and retain it in position for engagement by a reciprocating feeding tooth 21.

Located beneath the stack is a reciprocating feed bar 22 on which feeding projections or teeth 21 are mounted, the teeth being adapted to engage the rear end flap of the bottom slide in the stack and feed the slide forwardly through the space between the tongue 16 and stop 17 to a pair of feed rolls 23, 24 by which the slide is fed to appropriate mechanism for subsequent operations.

Mounted below the stack is a suction cylinder 28 which is provided with an arm 29 pivoted on a horizontal axis 30 to a fixed part whereby the cylinder may be oscillated about said axis. The pivotal axis 30 of the cylinder is arranged forwardly of the cylinder and at the rear end a suction nozzle 31 is rigidly mounted upon the cylinder and projects upwardly therefrom. The upper end of the nozzle may comprise a flexible mouthpiece.

The cylinder is arranged so that when it is oscillated upwardly the nozzle 31 engages the lowest slide in the stack, the engagement conveniently taking place on the tuck-in flap 10b of the slide. On the downward oscillation of the cylinder 28 the suction nozzle 31 is adapted to draw down the tuck-in flap 10b of the slide and bring it past the spring stop 19 hereinbefore mentioned.

and into the path of the projection or tooth 21 of the feed bar 22.

The oscillations of the cylinder 28 are obtained by a rotary cam 32 engaging a roller 33 mounted upon the cylinder. The roller is mounted upon a spindle carried upon an eccentric mounting whereby the displacement of the nozzle relatively to the lowest slide may be adjusted. The cylinder may be held on to the cam by a suitable spring. The cam disc 32 also carries a crank pin 34 which is connected by a link 35 to a lever 36 pivoted at its lower end at 37 and connected at its upper end by a link 38 to the piston rod 39 of the cylinder whereby the piston 40 is reciprocated and the desired suction effect produced. At a suitable position a port 41 is provided in the cylinder wall, such port being adapted to be uncovered by movement of the piston in a left-hand direction to destroy the suction and release the slide from the suction nozzle at the appropriate moment.

The feed rolls 23, 24 deliver the slide to a further pair of feed rolls 25, 26 with which a reciprocating feeding tooth 27 is associated by 25 which the slide is finally delivered; for example, to the carrier of a rotary table of a packing machine.

The reciprocating feeding tooth 27 is pivoted upon an oscillatory lever 42 carried by a rock-shaft 43. This shaft has also mounted upon it a lever 44 to one arm of which a cam lever 45 is pivotally connected. The cam lever is provided with a roller 46 engaging the rotary cam 47 whereby the shaft 43 is rocked and the feeding tooth 27 reciprocated. The tooth 27 is spring-pressed and engages in a groove 48 in the support 49. The lever 42 and feeding tooth 27 are located in the space provided between the spaced surfaces of the feeding rolls 25 and 23 (see Figure 2). As the slide 10 is fed forward by the rolls 25 and 26 the feeding tooth 27 recedes and on its next forward reciprocation engages the rear edge of the slide so that when the rolls 25 and 26 impart no further feed the tooth 27 will take up the feed and deliver the slide to the rotary table or other appropriate mechanism.

The cam lever 45 is provided with a guiding slot 50 and the roller 46 is held up to the cam 50 by a spring 51.

The feeding teeth 21 are reciprocated by the crank disc 52 to which the tooth supporting slide 22 is coupled by a link 53. The crank disc 52 is mounted upon the shaft 54 which is driven from the cam shaft 55 by spur gears 56, 57, (see Fig. 2). The gear 56 also meshes with a gear by which the cam 47 is rotated and from the last mentioned gear a drive is derived for the feed rolls 23, 24 and 25, through spur gearing.

In operation the cam 32 swings the cylinder 28 and brings the nozzle 31 upwardly into contact with the lowest slide which is held onto the nozzle 31 by the suction produced by the outward movement of the piston. As the cam 32 continues to rotate the cylinder is lowered, bending down the flap of the slide. The rear edge of the slide is moved past the spring stop 19 and is thus prevented from springing back when released from the nozzle which occurs when the suction is destroyed by the piston moving past the port 41, (see Fig. 1). With the parts in this position the slide will still be supported upon the ledges 15. The feed bar 22 then moves forward, the teeth 21 therein engaging the lowered end of the slide and feeding the slide forward so that it

is released from the ledges 15. The slide thus moves forwardly and into the feed rollers 23, 24.

The feed rollers 23, 24 feed the slide into the second pair of rollers 25, 26 and finally the reciprocating tooth 27 abuts against the edge of the rear flap 10b and completes the feeding action.

It will be noted that the transverse walls of the forward stack guides 11 and 12 are cut away at their bottom ends so that they offer no obstruction to the feeding of the lowest slide from the stack. In this connection it will be noted that the slides are supported in the stack by a three-point suspension, i. e., by the rear ledges 15 and the central tongue piece 16 whereby their removal from the stack is greatly facilitated.

By upwardly inclining the supporting surface of the tongue piece 16 the tendency to feed two cards at the same time is avoided.

In the form of apparatus above described the rear supports 15 for the stack of slides are associated with the side walls of the slide. This leaves the tuck-in flaps and end walls as it were unsupported, with the possibility of more than one flap being sucked down at a time by the suction nozzle.

This possibility may be overcome according to the modification shown diagrammatically in Figures 4 and 5 in which the rear end of the slides are supported by their tuck-in flaps resting upon lateral supporting bars 58. These bars are laterally adjustable and are provided with nose portions having inclined ends 59.

Where the flap of the lowest slide is sucked down it is bowed as indicated in Figure 4 and for this reason it is preferred to shape the hold-down spring stop 19 by forking the lower end, as at 19x in Fig. 4.

In view of the bowing of the slide-flap it is necessary to shape the ends of the reciprocating teeth 21 so that only point contact is obtained at first which is followed by a fall with feeding contact. This is done by inclining the upper edge 21a as will be seen in plan in Figure 4. This ensures the teeth 21 first engaging the bowed flap at the lowest point and as near to the spring stop 19 as possible.

In addition to ensuring that only one slide is sucked down at a time, the bowing of the slide flap makes a more rigid card for pushing from the bottom of the stack when the feed teeth 21 come into action.

The ledges 15 may be retained as these may be found useful in supporting the stack of slides while adjusting the positions of the supporting bars 58.

It will be obvious that the invention is not limited to the feeding or positioning of the slides of slide and shell cartons but may be applied to the feeding of other cards or sheets from a stack.

I claim:

1. In mechanism for feeding cards, such as the slides of slide and shell cartons, from a stack, wherein a reciprocating tooth feeding device successively feeds the cards from the bottom of the stack, card displacing means comprising a suction cylinder mounted to oscillate toward and from the lowermost card of the stack, and provided with a reciprocable piston, a suction nozzle having a flexible mouthpiece movable with said cylinder, means for oscillating the cylinder to advance the nozzle into contact with the lowest card and to displace the card into the path of a reciprocating feed tooth, and means synchronized with the cylinder oscillating means for causing relative movement between said oscillat-

- ing cylinder and its piston to produce the suction effect.
2. Mechanism for feeding cards from a stack as claimed in claim 1, wherein a rotary cam is provided for oscillating the cylinder, said cam engaging a roller carried by the cylinder.
3. Mechanism for feeding cards from a stack as claimed in claim 1, wherein a rotary cam is provided for oscillating the cylinder, said cam 10 engaging a roller carried by the cylinder, said roller being adjustable relatively to the cylinder.
4. Mechanism for feeding cards from a stack as claimed in claim 1 wherein a rotary cam is provided for oscillating the cylinder, said cam 15 engaging a roller carried by the cylinder, a crank carried by the cam shaft, said crank coupled to a pivoted lever, said lever coupled to the piston of said oscillating cylinder.
5. Mechanism for feeding cards from a stack 20 as claimed in claim 1, wherein a stop is provided for holding the displaced card in the path of the reciprocating feed tooth when the suction effect ceases, the oscillating cylinder drawing down the rear edge of the lowest card past said stop.
- 25 6. Mechanism for feeding cards from a stack as claimed in claim 1 wherein a leaf spring stop lies in the path of the displaced card for holding the card in the path of the reciprocating feed tooth when the suction effect ceases, the oscillating cylinder drawing down the rear edge of the lowest card past the stop.
- 30 7. In mechanism for feeding cards from a stack such as the slides of slide and shell cartons, a reciprocating tooth feed for successively feeding the cards from the bottom of the stack, stack supporting means affording a three-point support, comprising a pair of supporting elements for the rear of the slide and a forward central element having a stationary, transversely curved 35 card engaging surface which is upwardly inclined in the direction of feed.
- 40 8. Mechanism for feeding cards from a stack as claimed in claim 7 wherein a vertically adjustable gate element is located above the forward supporting element.
- 45 9. Mechanism for feeding cards from a stack as claimed in claim 7 wherein a vertically adjustable gate element is located above the forward supporting element, the opposed surfaces of said
- elements being curved transversely of the direction of feed to present line contact for the cards.
10. Mechanism for feeding slides from a stack as claimed in claim 7 wherein the rear supporting elements engage the rear tuck-in flaps of the 5 slides, the supporting surfaces of said elements being inclined, said elements being laterally adjustable.
11. Mechanism for feeding slides from a stack as claimed in claim 7 wherein the rear supporting elements engage the rear tuck-in flaps of the 10 slides, the reciprocating tooth feed comprising a pair of spaced teeth the card engaging parts of which are rearwardly and outwardly inclined.
12. Mechanism for feeding cards from a stack 15 comprising an oscillating suction cylinder having a suction nozzle for engaging a card and displacing it into the path of a reciprocating feed tooth, said tooth delivering the cards to spaced pairs of feed rolls, a table over which said rolls 20 advance each card, said table having a recessed face, and another reciprocating tooth device having a tooth adapted to slide in said face recess for engaging the rear edge of a card to feed said card when it has passed out of the influence of 25 said feed rolls.
13. Mechanism for feeding cards as claimed in claim 12 wherein said tooth device is mounted upon an oscillating lever and in which provision is made of a rotary cam for rocking said lever, 30 said cam being driven from the means which oscillate the suction cylinder.
14. In mechanism for feeding cards, such as the slides of slide and shell cartons, from a stack 35 wherein a reciprocating tooth feeding device successively feeds the cards from the bottom of the stack, card displacing means comprising a suction cylinder mounted to oscillate about a horizontal axis, and provided with a reciprocable piston, a suction nozzle rigidly mounted on the 40 cylinder, means for oscillating the cylinder to raise the nozzle into contact with the lowest card and displace the card into the path of a reciprocating feed tooth, and means synchronized with the cylinder oscillating means for reciprocating 45 the piston of said cylinder to produce the suction effect.

JOHN CRIGHTON.
